FIG 4

UNITED STATES PATENT OFFICE

ROBERT G. CLARK, OF BROOKLYN, NEW YORK

CIRCULAR LOOM

Application filed March 16, 1928. Serial No. 262,161.

My invention relates to looms of the circular type and has for its main objects and advantages to provide a loom on which weaving may be done at a much greater speed than formerly possible and by which a material saving is effected by the elimination of selvages from the finished fabric. Another object is to provide a loom on which a great variety of textures and color combinations may be woven and which may be set up or made ready with a minimum expenditure of labor.

A further object is to provide a loom of comparatively simple construction, having no parts readily broken or apt to get out of order, and in which all the parts are readily accessible. A still further object is to make the loom thoroughly automatic in all its operations, so that but slight skill is demanded of its operator.

These and various other objects and advantages will be plainly understood from the following description and from the accompanying drawings of a preferred embodiment, but it will be understood that many modifications may be made without departing from the scope of the invention.

In the drawings,

Fig. 1 is a side elevation of the loom, shown partly in cross-section;

Fig. 2 is a plan view;

Fig. 3 is a cross-sectional, side elevation of a part of the loom;

Fig. 4 is a fragmentary top view, principally to show the revolving shuttles;

Fig. 5 is a fragmentary top view of a certain cam;

Fig. 6 is a fragmentary perspective view of another cam;

Fig. 7 is a fragmentary side view of still another cam; and

Fig. 8 is a side elevation of some auxiliary parts.

The views are drawn to different scales and, to simplify the drawings, parts have been omitted from some of the views.

In a general way the loom may be said to consist of a circular table 10 on top of which, and adjacent to its periphery, are placed a plurality of bobbins 11. The warp threads

12, as they are unwound from these bobbins, are engaged by the heddles 13 and 13^a and passed through a circular throat 14 which is placed concentric with the table but at a considerable distance above it. As the heddles alternately lift and lower the warp threads, a plurality of revolving shuttles 15 weave the weft threads between these. The material 16, which is woven cylindrical or tubular, passes over a roll 17 and is finally wound on a friction driven roll 18.

The machine will now be described in detail and reference is now made to Figs. 1 and 3. The table 10 is supported by four posts 19 which also support the upper frames of the loom. The loom is driven by power imparted to the pulley 20. This pulley is attached to the main shaft 21 which revolves in the double bearing 22 and it is provided at its other end with a worm 23 which drives a wormgear 24. The wormgear is contained in the casing 25 and is rigidly attached on a turned down shoulder formed on the cast iron disc 26. This disc wheel rotates horizontally on the stationary, center shaft 27 which is rigidly mounted in the vertical bearing 28 formed on the cross frame 29, which is also supported by the posts 19 at a distance below the table 10.

Heddle-actuating cams 30 and 31 extend upwardly and outwardly from the periphery of the disc wheel 26 and these cams are separated by a spacing member 32. Fragments of these parts are shown in Fig. 7, their functions will be explained later. An annular gear 33 is also attached to this disc wheel. This gear ring drives a pinion 34 which is pinned to a short shaft 35. The shaft 35 rotates in a bearing 36 cast on the stationary disc 37 which is attached to the center shaft 27 so as to prevent rotation. An annular thread spacer 38 is attached to an upwardly extending, annular shoulder 39 formed near the periphery of the disc, and an annular seat 40 is formed on top of the disc.

A pinion 41 is pinned to the upper end of the shaft 35 and drives a gear ring 42 which is attached to the crown-spiral gear 43. This gear rotates on the center shaft 27. The

teeth 44 of the spiral gear are cut in a rim extending upwardly from its upper face. Another gear ring 45 is secured on the spiral gear. The gear ring 45 drives a pinion 46 which is pinned to another short shaft 46^a. This shaft turns in a bearing 47 cast on the stationary disc 48. This disc is also rigidly attached to the center shaft 27 so as to prevent it from rotating. A plurality of bearings 49 extend radially from the periphery of the disc 48, and in these bearings spiral pinions 50 rotate on shafts 51. The locations of these bearings and pinions are plainly shown on Fig. 4 and it will be seen that all these pinions mesh in the teeth 44 cut on the gear 43. These pinions actuate the shuttles, but this will be explained later.

A pinion 52 is pinned to the upper end of shaft 46^a and drives the gear ring 53 which is secured to the circular casting 54. This casting, which is free to rotate on the center shaft 27, consists of a lower, circular flange 55 and an upper cone 56. This cone is provided with a circumferential cam 57 cast integral with it, and an upper and lower cams 58 and 59 which are secured in seats formed on it. Fragments of these cams are shown in Figs. 5 and 6.

The warp threads 12 are carried upward through an eye 60, then through a tension device 62, a spring-actuated tension arm 63 and through an eye in a spacing ring 64, before being engaged by the heddles 13 and 13^a. The eye 60 and the tension devices 62 and 63 are formed and supported on wire standards 61, and these standards are mounted on a ring 65, made of insulating material. A metal ring 66 is placed in a seat in the insulating ring and the tension arm 63 is so constructed and proportioned that, if the thread 12 breaks, the arm will snap down and contact with the ring 66, as shown in the dotted position at 63^a. If the arm 63 and ring 66 are connected by wires 67 and 68 to an electric switch, the breaking of any warp thread will cause the loom to stop. To facilitate the bobbins' removal from the spindles 69 on which they are mounted, the spindles are attached on spiral springs 70.

50 The warp threads, after passing through the spacing ring 64 which has a notch for each thread, are engaged by the heddles which lift and lower each alternate thread; these motions being imparted to the heddles by the cams 30 and 31. The threads then pass through the thread spacers 38 and 71 and are gathered through the throat 14. This throat consists of a circular bushing 72, inserted in a frame 73 which is supported on the posts 19 some distance above the parts so far described. The thread spacer 71, which is shown in Figs. 1 and 3, consists of a plurality of segments provided with slots 74 and each 65 of these segments are supported on swinging

arms 75, adjustably hinged in bearings 76 which are cast on the frame 73.

The table, which is cast with a concentric opening, has two seats in which annular heddle guides 77 and 78 are secured. These 70 guides are provided with open slots in which the needles slide.

The construction of the shuttles 15 and the manner in which they are revolved will now be explained. The shuttles are, preferably, 75 made of sheet metal and each consists of a back plate, the contour of which is readily seen by referring to Fig. 4. The back plate may be said to be triangular in shape and has a toe 79, a heel 80 and a weft thread delivery 80 point 81. An apron 82 turns upwardly and some distance rearwardly and supports a thread tension device 83 which exerts the correct tension on the weft thread 84 which is contained on the shuttle bobbin 85. Thread 85 guiding ribs 86, 87 and 88 are secured to the back plate and the shuttle bearing 89 is secured to one of these ribs. The bobbin spindle 90 being hinged to facilitate removal of the bobbin. Each shuttle is provided with a spiral geared segment 91 which engages with several of the pinions 50. The bearings 49 are provided with guides 92 which dovetail between the segments 91 and the ribs 93, thus forming a continuous track for the shuttles 95 as they are revolved by the pinions 50. As previously stated, the pinions are actuated by the spiral gear 43. An angular cut 94 narrows down the outer, upper corners of the bearings 49 so as to allow the warp thread to 100 straddle them.

As already stated, motion is imparted to the heddles by the cams 30 and 31. The engaging surfaces of the cams are wavy, as shown in Fig. 7, and each alternate heddle has 105 a portion cut out of its lower end so that alternate heddles are operated, respectively, by cams 30 and 31. This is clearly shown in Fig. 3, where heddle 13 is engaged in the bottom of a wave, as at 95 in Fig. 7, and heddle 13^a 110 is engaged on top of a wave, as at 96 in Fig. 7.

The heddles are slotted at the upper ends and the warp threads engage in these slots. As each alternate warp thread is lifted, the toe 79 enters between the threads and the threads 115 are further separated by the shuttle as it passes between them. The further separation being caused by the back of the shuttle, the apron 82 and the various ribs contained on the shuttle.

As the shuttles revolve the weft threads 84 are laid between the warp thread and forced into their proper place by the weft-engaging fingers 97, which are mounted on the cam 57 and actuated by this cam and the cams 58 and 59. These fingers are, as shown in Fig. 3, held in position by the cam 57 and they are spaced, radially, by slotted spacer rings 98 and 99. The ring 98 being rigidly secured to the stationary shaft 27 and the 120

ring 99 mounted on upright supports 100 which are cast on the stationary disc 48.

A fulcrum 101, formed substantially central of the length of the fingers, engage 5 against a conical ring 102 which is supported on top of the upright supports 100. The conical ring 102 clamps the spacer ring 99 in place. The toes 104 of the fingers are moved forward and backward by the actions of the 10 cams 58 and 59; the fingers rocking on the fulcrums 101. This will be easily understood by an examination of the depressions 105 and 106 in cams 58 and 59, as shown in Fig. 5. An examination of Fig. 6 will also show that, 15 as the cone 56 revolves, the fingers are lowered each time the depressions 103 in the cam 57 pass behind them. It will thus be seen that as the shuttles revolve, the toes 104 enter between the warp threads and, moving upward, 20 engage the weft threads, placing them in their correct position. After the weft threads are in place, the toes are lowered and drawn rear- 25 wardly out of engagement so as to allow the next shuttle to pass.

The finished material 16, which as will be noted is woven cylindrical or tubular, passes up through the throat 14, being fed upwardly by the toes 104. A circular collar 107, slide- 30 ably mounted on a turned down portion of the shaft 27, is located in the throat to help guide the material under certain conditions. The material as it is woven passes over the roller 17 and is wound on the roller 18; both 35 these rollers being supported on an upper frame 109 attached on the posts 19. The roller 18, which is friction driven by a spring 110, is actuated from the main shaft 21. A bevel gear 111 is secured on this shaft and drives another bevel gear 112, secured on a 40 vertical shaft 113. On the upper end of this shaft a worm 114 is secured which drives a worm gear 115, secured on the roller shaft 116.

It will now be seen that, while it was stated 45 earlier that the material was fed by the toes 104, the material may also be drawn upward by the drum 18. In this manner it is possible, by varying the tension on this drum, to weave fabrics with more or less open tex- 50 ture. It will also be clear that as a plurality of shuttles are employed, various color combi- 55 nations may be obtained. In like manner, various designs may be woven by not oper- 60 ating alternate heddles on the cams 30 and 31 as described, but, for example, by operating two heddles on cam 30, then two heddles on cam 31 and so on, alternating the heddles on these cams in various combinations.

In starting the loom, the warp threads are 65 gathered together as shown in Fig. 8, tied to a cord which passes over the rollers 17 and 18, and drawn taut by a weight 118. As soon as sufficient material is woven, it is attached on the roller 18 and the weight 118 removed.

Having described my invention, what I

claim as new and wish to protect by Letters Patent is:

1. In a circular loom; a plurality of bobbins supplying the warp threads; a plurality of radially disposed independent heddles en- 70 gaging said warp thread; two heddle-actuating cams for lifting alternate warp threads; said heddles being interchangeable so that they may be arranged in various combinations on their respective cams; one or more 75 shuttles supplying the weft thread; and means for revolving said shuttle or shuttles through the alternated warp threads.

2. In a circular loom; a plurality of bobbins supplying the warp thread; a plurality of radially disposed independent heddles en- 80 gaging said warp thread; one or more shuttles supplying the weft thread; two heddle-actuating cams for lifting certain warp threads and depressing others so that the 85 shuttle or shuttles may pass under said lifted and over said depressed threads; said heddles being interchangeable so that they may be arranged in various combinations on their respective cams; and means for revolving 90 said shuttle or shuttles.

3. In a circular loom; a plurality of bobbins supplying the warp thread; a plurality of radially disposed independent heddles en- 95 gaging said warp thread; one or more shuttles supplying the weft thread; two heddle-actuating cams for lifting certain warp threads and depressing others so that the 100 shuttle or shuttles may pass under said lifted and over said depressed threads; said heddles being interchangeable so that they may be arranged in various combinations on their respective cams; means for revolving said shuttle or shuttles; and a plurality of fingers for correctly placing said weft thread. 105

4. In a circular loom; a plurality of bobbins supplying the warp thread; a plurality of radially disposed independent heddles en- 110 gaging said warp thread; one or more shuttles supplying the weft thread; two heddle-actuating cams for lifting certain warp threads and depressing others so that the 115 shuttle or shuttles may pass under said lifted and over said depressed threads; said heddles being interchangeable so that they may be arranged in various combinations on their respective cams; means for revolving said shuttles; and a plurality of fingers for correctly placing said weft thread while feeding the finished material. 120

5. In a circular loom; a plurality of bobbins supplying the warp thread; a plurality of radially disposed independent heddles en- 125 gaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be 130

- arranged in various combinations on their respective cams; means for revolving said shuttle or shuttles; and means for spacing the warp threads to prevent their displacement by the shuttle or shuttles passing between them.
6. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttles may enter between said lifted and said depressed threads; said heddles being interchangeable so that they may be arranged in various combinations on their respective cams; means for revolving said shuttles; and means provided on the shuttles for further lifting and depressing the warp threads as they pass therebetween. 70
- 10 75
7. In a circular loom; a plurality of bobbins supplying the warp threads; a plurality of radially disposed independent heddles engaging said warp threads; two heddle-actuating cams for lifting alternate warp threads; said heddles being interchangeable so that they may be arranged in various combinations on their respective cams; one or more shuttles supplying the weft thread from a bobbin contained therein; said bobbins rotating on hinged spindles to facilitate their removal; and means for revolving said shuttles through the alternated threads. 80
- 15 85
8. In a circular loom; a plurality of bobbins supplying the warp threads; said bobbins rotating on spindles having flexible attaching means; a plurality of radially disposed independent heddles engaging said warp threads; two heddle-actuating cams for lifting alternate warp threads; said heddles being interchangeable so that they may be arranged in various combinations on their respective cams; one or more shuttles supplying the weft thread; and means for revolving said shuttles through the alternated threads. 90
- 10 95
9. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be arranged in various combinations on their respective cams; means for revolving said shuttles; a plurality of fingers for correctly placing the weft threads while feeding the finished material; a circular throat through which the material is fed; and a friction driven roller for winding the finished material as finished; and means for adjusting the friction on said roller so that the finished material may be advanced at a greater speed than that imparted by the said weft-engaging fingers. 100
- 15 105
- 10 110
11. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be arranged in various combinations on their respective cams; means for revolving said shuttles; a plurality of fingers for correctly placing the weft threads while feeding the finished material; a circular throat through which the material is fed; and a roller for winding the finished material; said roller being friction driven. 115
- 10 120
12. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be arranged in various combinations on their respective cams; means for revolving said shuttles; a plurality of fingers for correctly placing the weft threads while feeding the finished material; a circular throat through which the material is fed; and a roller for winding the finished material; said roller being friction driven. 125
- 10 130
13. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be arranged in various combinations on their respective cams; means for revolving said shuttles; a plurality of fingers for correctly placing the weft threads while feeding the finished material; and a circular throat through which said material is fed.
- 10 135
14. In a circular loom; a plurality of bobbins supplying the warp thread; a plurality

respective cams; means for revolving said shuttles; a plurality of fingers for correctly placing the weft threads while feeding the finished material; a circular throat through which the material is fed; a roller for winding the finished material; and an intermediate roller for spreading the cylindrically woven material prior to its winding on the first mentioned roller.

10 14. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttle or shuttles may pass under said lifted and over said depressed threads; said heddles being interchangeable so that they may be arranged in various combinations on their respective cams; means for revolving said shuttles; a plurality of fingers for correctly placing the weft threads while finishing the material; a circular throat through which the finished material is fed; and a slidable collar located inside the throat.

15. In a circular loom; a plurality of bobbins supplying the warp threads; a plurality of radially disposed independent heddles engaging said warp threads; two heddle-actuating cams for lifting alternate warp threads; said heddles being interchangeable so that they may be arranged in various combinations on their respective cams; one or more shuttles supplying the weft thread; means for revolving said shuttles between the alternated threads; and automatic means for stopping the loom; said means being actuated by the breaking of any warp thread.

20 16. In a circular loom; a plurality of bobbins supplying the warp thread; a plurality of radially disposed independent heddles engaging said warp thread; one or more shuttles supplying the weft thread; two heddle-actuating cams for lifting certain warp threads and depressing others so that the shuttles may pass under said lifted and over said depressed threads; said heddles being interchangeable so that they may be arranged in various combinations on their respective cams; means for revolving said shuttles; slotted rings for spacing the warp thread and preventing displacement thereof; one of said rings being formed of segments; and each of said segments swingably mounted.

ROBERT G. CLARK.
